UNITED STATES PATENT OFFICE.

ROBERT M. McLAIN, OF HUNTSVILLE, ALABAMA.

DESIGN FOR A STEERING-WHEEL.

46,441.

Specification for Design.

Patented Sept. 22, 1914.

Application filed June 19, 1914. Serial No. 846,210. Term of patent 14 years.

To all whom it may concern:

Be it known that I, ROBERT M. McLAIN, a citizen of the United States, residing at Huntsville, in the county of Madison and State of Alabama, have invented a new, original, and ornamental Design for Steering-Wheels, of which the following is a specification, reference being had to the accompanying drawing, forming a part thereof.

Figure 1 is a side elevation illustrating my design; and Fig. 2 is a bottom plan view.

I claim:

The ornamental design for a steering wheel, as shown.

ROBERT M. McLAIN.

Witnesses:

H. E. GRIZZARD,
R. E. CALDWELL.
